ABSTRACT: An attachment for an otherwise conventional single needle sewing machine which functions automatically to effect stopping of the needle in a raised position when operation of the machine is interrupted, to enable the operator to thread the needle or to remove the material being sewed without manually turning the hand wheel, to thus save time and labor.

FIG. 1.

FIG. 2.

INVENTOR
PAUL C. TRILLI

BY *John N. Randolph*
ATTORNEY

SEWING MACHINE NEEDLE POSITIONER

SUMMARY

A primary object of the present invention is to provide a completely mechanical attachment of extremely simple construction which may be readily applied to a conventional single needle sewing machine to automatically cause the needle to stop adjacent an extremity of its reciprocating travel when operation of the machine is interrupted.

Another object of the invention is to provide such an attachment which functions completely automatic, without any special action on the part of the operator.

Various other objects and advantages of the invention will hereinafter become more fully apparent from the following description of the drawing, illustrating a presently preferred embodiment thereof, and wherein:

BRIEF DESCRIPTION OF THE DRAWING

FIG. 1 is a fragmentary side elevational view of a conventional single needle sewing machine, showing the needle positioner attachment applied thereto;

FIG. 2 is an enlarged fragmentary vertical sectional view, partly in side elevation, showing parts of the attachment and conventional parts of the sewing machine with which said attachment parts are associated, and

FIG. 3 is an enlarged horizontal sectional view, taken substantially along a plane as indicated by the line 3-3 of FIG. 1.

DETAILED DESCRIPTION OF THE PREFERRED EMBODIMENT

Referring more specifically to the drawing, the needle positioner attachment in its entirety and comprising the invention is designated generally 5 and is shown applied to a conventional single needle sewing machine, portions only of which have been illustrated and will be described only to the extent necessary to set forth the application of the attachment thereto.

The sewing machine, designated generally 6, includes a needle bar 7 which is mounted for vertical reciprocating movement in a needle bar bushing 8, and which supports a needle 9 at its lower end in a conventional manner. The conventional means to effect reciprocating movement of the needle bar 7 has not been illustrated.

The positioning attachment 5 includes a cylinder 10 having a restricted tubular neck 11 at its lower end which engages over the exposed upper end of the bushing 8 and which is detachably secured thereto by a setscrew 12.

The upper end of the needle bar 7, which protrudes from the upper end of the bushing 8, extends into the cylinder 10 and said upper end is provided with an internally threaded upwardly opening socket 13, which constitutes the only modification of the sewing machine 6. A piston, designated generally 14, is secured to the upper end of the needle bar 7 and operates in the cylinder 10. Said piston includes two discs 15 and 16 of diameters less than the internal diameter of the cylinder 10 and a cup shaped washer 17 which is clamped between the discs 15 and 16 by a headed screw 18 which extends centrally through the parts 15, 16 and 17, and which is threadedly received in the socket 13 for attaching the piston 14 to the needle bar 7. The down turned annular peripheral portion 19 of the washer 17 slidably engages the wall of the cylinder 10.

The cylinder 10 has a top wall 20 which is suitably secured thereto after attachment of the piston 14 to the needle bar 7. The wall 20 has an opening or port 21. A lower portion of the cylinder 10 is provided with a vent port 50.

A bracket arm 22 is secured to and extends outwardly from an upper portion of the cylinder 10 and has an upturned outer end 23 provided with an opening 24. A lever 25 has a pair of transversely spaced ears 26 extending downwardly therefrom and which straddle a part of the bracket 22, which is located adjacent the cylinder 10, and which are connected thereto by a pivot element 27 for mounting the lever 25 above the

bracket 22 and cylinder 10 and for rocking movement relative thereto. A dislodge valve element 28 is secured by fastening means 29 to the under side of the lever 25, remote from its pivot 27 and is positioned to engage and close the port 21. The lever 25 has an upturned end 30 located on the opposite side of the pivot 27 from the valve 28 and which is spaced from the upturned bracket end 23.

A flexible wire 31 extends through and is slidably disposed in a flexible tubing 32. One end of the tubing 32 is secured in the bracket opening 24 by setscrew 33. One end of the wire 31 extends from said tubing end through an opening 34 in the upturned lever end 30. A compression spring 35 is mounted on the wire 31 between the bracket end 23 and the lever end 30 for normally urging the lever 25 to rock counterclockwise about its pivot 27 for holding the valve 28 in a position for closing and sealing the port 21. A head 36 is secured to the terminal of said wire end and is disposed on the other side of the lever end 30 from the spring 35.

The wire 31 and tubing 32 have opposite downwardly extending lower ends and the wire 31 has a terminal portion which protrudes from said lower end of the tubing 32 and which is secured in an opening 37 of a block 38 by a setscrew 39, as seen in FIG. 3. Block 38 has a second opening 40 through which extends the treadle rod 41 of the sewing machine. A setscrew 42 secures the block 38 to the rod 41 for up and down movement therewith. The lower end of the treadle rod 41 is pivotally connected to an eye 43 secured to one end of a treadle 44 which is pivotally mounted at 45 intermediate of its ends. The opposite end of the treadle rod 41 is pivotally connected to a pivotally mounted lever 46 which closes a switch 47 of the electric motor 48 of the sewing machine when the treadle 44 is rocked in a direction to exert a downward pull on the treadle rod 40.

Accordingly, when the switch 47 is closed to energize the motor 48 to cause operation of the sewing machine 6, the downward movement of the treadle rod 40 will exert a downward pull on the end of the wire 31 connected to the block 38 to cause the other end of the wire 31, as seen in FIG. 2, to move from left to right, so that the head 36 will be pulled against the lever end 30 for rocking the lever 25 clockwise about its pivot 27 to elevate the valve element 28 and open the port 21. While the port 21 is open, the piston 14 can reciprocate freely in the cylinder 10 with the needle bar 7, since the cylinder 10 is vented below the piston 14 by the port 50.

When the treadle 44 is rocked in the opposite direction, or counterclockwise about its pivot 45 for elevating the treadle rod 40 to move the lever 46 to a position to permit the switch 47 to open and deenergize the motor 48 for stopping operation of the sewing machine 6, the wire end 31 attached to the block 38 will be displaced upwardly with said block through the tubing 32 and so that the end of the wire 31, as seen in FIG. 2, will be displaced from right to left through the opening 34 to move the head 36 away from the lever end 30 to allow the compressed spring 35 to return the valve 28 to its closed position by rocking the lever 25 in a counterclockwise direction. However, should the movement of the valve 28 to a closed position occur during upward travel of the piston 14 as the sewing machine coasts to a stop the pressure in the cylinder 10, above the piston 14, will rock the lever 25 clockwise against the action of the spring 35 to unseat the valve 28 to allow escape of air from the upper part of the cylinder 10 until the piston 14 reaches the upper extremity of its travel. When this occurs the spring 35 will promptly close the valve 28 to create a vacuum in the cylinder 10 above the piston 14 to check reciprocation of the piston, needle bar 7 and needle 9 and for thus stopping the needle in its raised position of FIG. 1, so that the needle can be threaded or the material being worked upon removed from the sewing machine without manually turning the wheel 49 to elevate the needle. If movement of the piston 14, needle bar 7 and needle 9 ceases during downward travel of said parts, the vacuum in the cylinder 10, above the piston 14, will return the parts to their raised position of FIGS. 1 and 2.

Various modifications and changes are contemplated and may be resorted to, without departing from the function or scope of the invention.

I claim:

1. In a sewing machine having a reciprocating needle bar, a bushing for said needle bar, a motor, a treadle and a treadle rod for operating said motor, a needle positioner comprising a cylinder attached to and disposed above said needle bar bushing, a piston secured to the upper end of said needle bar and disposed for operation in said cylinder, said cylinder having a vent port disposed beyond each extremity of travel of the piston, a valve for closing one of said vent ports, spring means normally urging said valve to a closed position, and valve actuating means connected to said valve and including a wire having one end connected to said treadle rod of the sewing machine whereby when the treadle rod is moved in one direction to effect engaging of the electric motor of the sewing machine a pull is exerted on the wire for moving the valve to an open position for venting said cylinder port to allow the piston to reciprocate freely in said cylinder, and when the treadle rod is moved in the opposite direction for deenergizing the motor, said spring means urges said valve to said closed position for sealing said port as the piston commences to move away from said port thereby creating a vacuum in the cylinder end containing said sealed port to resist travel of the piston away from said cylinder end thus stopping the needle bar and needle adjacent one extremity of movement of said parts.

2. A sewing machine needle positioner as in claim 1, said valve controlled port being disposed at the upper end of the cylinder for stopping movement of the piston adjacent the upper extremity of its travel whereby the needle will automatically be stopped in a raised position when operation of the

sewing machine is interrupted.

3. A sewing machine needle positioner as in claim 1, a bracket arm secured to and extending outwardly from an upper portion of the cylinder and having an upturned outer end provided with an opening through which a portion of the wire slidably extends, said valve actuating means including a lever pivotally mounted on the bracket arm and on which said valve is supported for swinging movement into and out of engagement with said port, said lever having an upturned end disposed between the lever pivot and the upturned end of said bracket arm and through which said wire slidably extends, said lever pivot being disposed between the valve and the upturned lever end, said spring means comprising a compression spring mounted on the wire between the upturned ends of the bracket arm and lever for urging the lever in a direction for moving the valve to a closed position, and a head connected to the wire and disposed on the other side of the upturned lever end for rocking the lever in the opposite direction for opening the valve when a pull is exerted on the wire by said movement of the treadle rod in a direction for closing the motor switch.

4. A sewing machine needle positioner as in claim 3, and a flexible tubing enclosing a substantial portion of said wire having one end secured in said bracket arm opening and an opposite end extending to adjacent the end of said wire which is connected to the treadle rod, said wire slidably engaging in said tubing.

5. A sewing machine needle positioner as in claim 4, a connecting element, means adapted to adjustably connect said connecting element to the treadle rod and means securing the wire to the connecting element beyond the end of the tubing located remote from said bracket arm.
